United States Patent Office

Des. 215,766
Patented Oct. 28, 1969

215,766

PAINT BOX

Rudolph Dusek, Mianus Roads, Cos Cob, Conn. 06807

Filed May 6, 1968, Ser. No. 11,804

Term of patent 14 years

Int. Cl. D19—07

U.S. Cl. D74—1

I claim:

The ornamental design for a paint box, as shown.
